MAT FOR MOUNTING TILE AND THE LIKE

Cora D. Holcomb, Akron, Ohio

Application October 26, 1936, Serial No. 107,588

1 Claim. (Cl. 72—24)

This invention relates to improvements in tile construction and has particular relation to improvements in means for mounting blocks of tile, rubber, wood, glass or other suitable material on a wall, floor or other surface to form a permanent covering therefor.

The use of tile as a floor or wall covering is very desirable, particularly in bathrooms. While tile can be manufactured at a low cost the process of mounting such covering is slow and requires the services of an expert workman. This results in a cost which greatly restricts the use of tile for this purpose.

Objects of the invention are to provide a tile construction of attractive appearance which can be quickly and accurately laid by an ordinary workman and which will provide a strong, durable construction at a low cost.

Other objects are to provide a material which can be nailed, glued or otherwise secured to the floor, wall or other surface and which will be provided on the outwardly presented face thereof with integrally formed stiles corresponding to joints between the tiles and forming sockets each adapted to snugly receive and hold the tile.

A further object is to provide a method and means for mounting tile which will securely hold the same in place and which can be used to mount smooth, imperforate blocks constructed of glass, rubber or any material which cannot be securely held in place in tile structures of ordinary construction.

The above objects are accomplished and additional ends are attained by the novel construction, combination and arrangement of parts herein-after described and illustrated in the accompanying drawing wherein there is shown a preferred form of the invention, it being understood that changes and modifications may be made or resort had to substitutions which come within the scope of the claim hereunto appended.

In the drawing:

Figure 1 is a plan view of a portion of a mat employed in my improved tile construction,

Figure 2 is a similar view showing tile operatively mounted therein,

Figure 3 is a cross sectional view taken as indicated by the lines 3—3 of Figure 1,

Figure 4 is a perspective view of one of the tiles or blocks constructed in accordance with this invention,

Figure 5 is a vertical, sectional view of a wall construction taken as indicated by the lines 5—5 of Figure 2.

55 In the particular adaptation of the invention

illustrated, there is shown a mat 6 which is preferably formed of rubber, rubber composition or other similar material and which is provided on the forward face thereof with integrally formed stiles 9 and 10. The stiles 9 are arranged in 5 parallel, spaced relation to extend across the mat in one direction and the stiles 10 are likewise arranged transversely of the stiles 9. The stiles 9 and 10 are preferably rectangular in cross sectional shape and are arranged with the 10 outwardly presented faces thereof disposed in the same plane. The stiles 9 and 10 thus form a plurality of sockets 7, each adapted to snugly receive a block 8, which when positioned therein will be disposed with its forward face substantially flush 15 with the forward face of the stiles 9 and 10.

The mat 6 including the rear wall 6a and the stiles 9 and 10 are preferably composed of elastic rubber whereby a block 8 may be forced into each socket 7 and will be retained therein by the elasticity of said stiles. When the back wall 6a of the mat 6 is formed of relatively stiff material, it is provided within each socket 7 with a plurality of openings 11 for a purpose presently to appear.

In Figure 5 there is shown a wall construction in which the numeral 14 denotes a studding and the numeral 13 sheathing which is secured to the studding 14 in the ordinary manner. A mat 6 is positioned against the sheathing with the 30 stiles 9 and 10 positioned outwardly and nails or other fastening means 12 are entered through the openings 11 and driven into the sheathing 13 thus securely mounting the mat 6 on the sheathing 13.

While blocks 8 composed of any material will be retained in the sockets 7, I prefer to use suitable adhesive which is applied to the walls of each socket 7 for the purpose of positively retaining the blocks therein. The blocks 8 are preferably 40 formed to fit in the sockets 7 flush with the outer faces of the stiles 9 and 10.

While the mat 6 and the stiles 9 have been described as preferably formed of elastic rubber, it is understood that the mat is in a fully vul- 45 canized or finished form before it is secured to a wall or other supporting structure and before the blocks 8 are inserted in the sockets 7.

It will be seen that the outwardly presented faces of the stiles 9 and 10 will have the appearance of mortar joints and that such joints will be of uniform thickness. It will also be seen that the walls of each socket 7 will form a cushion which will protect the blocks 8 against breakage. As the stiles 9 and 10 are composed of elas- 55

tic rubber, blocks 8 varying slightly in size may be used.

Having thus illustrated and described a preferred form of the invention, what I claim as new and desire to secure by Letters Patent is:—

In a tile construction, a mat of completely vul-

canized elastic rubber having a plurality of cavities on the outer face thereof, each of said cavities adapted to receive and hold a block which when forced therein will be held in place by the elasticity of said stiles.

CORA D. HOLCOMB.
